LIQUID DISPENSER FOR CLOTHES WASHERS AND THE LIKE

Keith A. Edwards, Schenectady, N. Y., and William R. Buechler, Louisville, Ky., assignors to General Electric Company, a corporation of New York

Application October 22, 1952, Serial No. 316,274

11 Claims. (Cl. 68—17)

The present invention has to do primarily with automatic clothes washing machines and the like and has for its object to provide improved means for supplying to such a machine during one or more of its washing operations along with the cleansing liquid a suitable or desired washing agent. The term cleansing liquid as used herein is intended to include water or other washing or cleansing liquid and the term washing agent is intended to include any liquid sanitizing or germicidal agent, a liquid detergent, or other liquid substance or liquid solution which it is desired to supply to the machine along with the cleansing liquid.

According to the invention cleansing liquid is supplied to the machine through an aspirator, the cleansing liquid serving as a pumping liquid or vacuum producing liquid for the aspirator, and the washing agent is pumped into the machine by the aspirator; and in connection therewith there is provided means for controlling the aspirator whereby when cleansing liquid is flowing through it, a washing agent may or may not be pumped as found desirable. For example, in the case of a clothes washing machine, it may be desirable to supply a sanitizing or germicidal agent to the machine along with the rinse water in which case the aspirator would be made effective to pump such agent to the machine when rinse water is being supplied to it but not at other times.

For a consideration of what we believe to be novel and our invention attention is directed to the following specifications and to the claims appended thereto.

In the drawing, Fig. 1 is a side elevation partly in section of a clothes washing machine embodying the invention; Fig. 2 is a top plan view with parts broken away of a corner of the clothes washing machine showing the improved liquid supplying means; Fig. 3 is a sectional view taken on line 3—3, Fig. 2; Fig. 4 is a sectional view taken on line 4—4, Fig. 2; Fig. 5 is a wiring diagram; Fig. 6 is a view similar to Fig. 2 of a modification; Fig. 7 is a detailed sectional view taken on line 7—7, Fig. 6, and Fig. 8 is a diagram illustrating the operation of the modification shown in Figs. 6 and 7.

Referring to the drawing, a clothes washing machine of known type is shown in outline in Fig. 1, it being a machine of the single tub spin basket type. It comprises an outer casing 1, a tub 2, a spin basket 3 and an agitator 4. Mechanism including an electric motor for oscillating the agitator 4 for washing and for rotating spin basket 3 for extracting cleansing liquid from the clothes is contained in a casing 5. The lid for the machine is indicated at 6 and the spout through which cleansing liquid is supplied to the machine is indicated at 7.

The structure so far described is shown only by way of example. It is to be taken as typical of any suitable clothes washing machine.

According to our invention we supply cleansing liquid from a source of suitable pressure to the machine through an aspirator which serves to pump into the machine along with the cleansing liquid a suitable washing agent. The aspirator comprises a tapered nozzle 10, the discharge

end of which is positioned in the inlet end of spout 7. In the inlet end of nozzle 10 is a cleansing liquid supply pipe 11 which discharges liquid through nozzle 10 and spout 7 to spin basket 3. The supply pipe 11 may connect with a desired source of cleansing liquid under suitable pressure; in the case of the ordinary household washing machine with the domestic water supply system.

Mounted on the machine in the vicinity of but below the aspirator is a container 12 for a liquid washing agent, the interior of the container at a region adjacent to its bottom being connected to nozzle 10 by an aspirator tube 13 which connects with the interior of nozzle 10 through an aspirator opening 14. With this arrangement when cleansing liquid flows from pipe 11 past opening 14, washing agent may be drawn up from container 12 through tube 13 and fed through opening 14 into the flowing stream of cleansing liquid in accordance with the well understood operation of aspirators of this type. Container 12 is provided with a filling and vent opening 14'.

For controlling the operation of the aspirator, there is provided in aspirator tube 13, an air bleed opening 15 controlled by a valve 16. When valve 16 is in open position, the aspirator will function to draw or pump only air, but when the valve is closed, closing bleed opening 15, then the aspirator will function to pump washing agent.

In connection with the aspirator, there is provided on the upstream side of opening 14 as regards the direction of flow of cleansing liquid an inwardly projecting lip 10' which points angularly downstream as shown clearly in Figure 3, extending partly over the opening 14. This lip performs an important function in that it deflects the stream of cleansing liquid slightly as indicated by the flow lines in Fig. 3 so that the cleansing liquid does not strike the opposite side of the aspirator opening 14. Thus, the cleansing liquid is prevented from entering the pipe through which the washing agent flows and diluting the washing agent as well as filling the washing agent container with cleansing liquid. Also, by preventing the cleansing liquid from striking the opposite side of opening 14, the lip 10' reduces the flow disturbance in the stream of cleansing liquid and creates a better vacuum for drawing the washing agent into the stream of cleansing liquid.

In the arrangement illustrated by Figs. 1 through 4, aspirator opening 14 is in the top of nozzle 10. Hence when there is a low flow rate from pipe 11, there is no risk of washing liquid leaking or flowing downwardly through pipe 13 into the container for the cleansing agent.

In connection with the aspirator, it should also be noted that it is an open type, the end of pipe 11 which conducts the cleansing liquid into the aspirator conduit 10 being separated by an open space from the aspirator opening 14. Thus, if a vacuum were created in pipe 11, only air would be drawn into pipe 11, not the washing agent, and no contamination of the plumbing by the washing agent could take place.

Valve 16 may be moved manually in the case of a manually controlled clothes washing machine or it may be moved automatically in the case of an automatically controlled machine. However, the invention is especially useful and applicable to an automatic clothes washing machine.

In carrying out our invention in connection with an automatic clothes washing machine, there is provided for operating valve 16 means which is embodied in and forms a part of the automatic control system, the arrangement being such that when the valve or valves which control the supply of cleansing liquid to the machine are opened to supply cleansing liquid for a particular

or desired washing operation, valve 16 will be closed when such supply valve or valves are opened to supply cleansing liquid only for other washing operations, valve 16 will be open. For example, the arrangement may be such that washing agent is supplied only when cleansing liquid is supplied for a rinsing operation.

For automatically closing and opening valve 16, its stem is connected to the free end of a coiled bimetal strip 17, the other end of which is mounted on a fixed support 18. Mounted adjacent to the bimetal strip for heating it is a heating element here shown in the form of an electric lamp 19. The arrangement is such that normally when the bimetal strip is cold, it holds valve 16 open. When heated it flexes toward the left as shown in Fig. 4 to close the valve. The control is such that during any cleansing liquid supply period when it is desired to supply a washing agent to the machine along with the cleansing liquid, the circuit of lamp 19 is closed to effect the closing of valve 16. Referring to the wiring diagram in Fig. 5, 20 indicates a solenoid operated cleansing liquid supply valve in pipe 11 and 21 indicates a timing motor driven automatic control timer which controls the circuits for operating valve 20 and the washing machine motor indicated at 22. At 23 is a timer operated switch which is closed to effect the opening of valve 20 and at 24 is a timer operated switch which is closed to effect operation of valve 16 by closing a circuit on heater lamp 19. The source of electrical supply is indicated at 25, the main control switch at 26 and circuits leading to motor 22 for other machine operations are indicated at 27. If desired a manually operated switch 28 located on the machine for convenient operation may be connected in the heater unit circuit so that the heater may be disconnected from the controller if the operator wishes not to supply washing agent when using the machine.

This showing is diagrammatic, only connections sufficient for an understanding of the invention being shown. Whenever timer switch 23 is closed valve 20 will be opened to supply cleansing liquid to the machine but the washing agent control valve 16 will be closed only at such times as timer switch 24 is closed also to close the circuit on heater lamp 19.

In Figs. 6, 7 and 8 is shown a modified arrangement for controlling the aspirator. In this modification in advance of the aspirator opening 30 (corresponding to the aspirator opening 14 of Figs. 1 to 4) as regards the flow of cleansing liquid, there is provided a deflector 31 in the form of a wire which is connected to a bimetal strip 32 and by it adapted to be moved down into and up out of the path of flow of cleansing liquid from the supply pipe 33 which corresponds to supply pipe 11 of Figs. 1 to 4 inclusive. Otherwise, the arrangement may be the same as that shown in Figs. 1 to 4 inclusive and corresponding reference characters have been applied to corresponding parts. When deflector wire 31 stands in the path of flow of cleansing liquid from pipe 33, the flow is caused to divide and pass to each side of the aspirator opening as illustrated diagrammatically in Fig. 8. As a result, no washing agent will be fed from tank 14 to the inflowing stream. However, when bimetal 32 is heated to move deflector wire 31 upward out of the path of the flowing stream then the liquid will flow over the aspirator opening, effecting the feeding of washing agent into the stream of cleansing liquid.

By our invention we effect the feeding of a washing agent to a clothes washing machine in an efficient manner and by the use of mechanism which is simple in structure and reliable in operation; and in addition by mechanism which can be supplied at low cost and readily fitted into an automatic control system.

What we claim and desire to secure by Letters Patent of the United States is:

1. In a clothes washing machine or the like having

4
a pipe for supplying cleansing liquid to the machine, an aspirator for feeding a liquid washing agent to the machine along with the cleansing liquid comprising a nozzle into which the discharge end of the cleansing liquid pipe projects and through which it discharges cleansing liquid to the machine, a container for a washing agent, an aspirator tube connecting said container to said nozzle through an aspirator opening in said nozzle located at a point beyond the end of said pipe as regards the direction of flow through it, movable means for rendering said aspirator opening effective and ineffective to draw up washing agent from the container to the nozzle, control means for the clothes washing machine, and means connected with said washing machine control means for actuating said movable means.

2. In a clothes washing machine or the like of the type having a control means and a pipe for supplying cleansing liquid to the machine, an aspirator for drawing a liquid washing agent into the machine along with the cleansing liquid comprising a nozzle into which the discharge end of the liquid supply pipe projects and through which it discharges cleansing liquid to the machine, a container for washing agent, an aspirator suction tube connecting said container to said nozzle through an aspirator opening in said nozzle located at a point beyond the end of said pipe as regards the direction of flow through it, said aspirator tube being provided with an air bleed hole, a valve for blocking flow of air through said air bleed hole, means for operating said valve, and means connected with the control means for actuating said valve operating means.

3. In a clothes washing machine of the type having a timer for controlling automatically washing operations including the supplying of cleansing liquid to the machine, means for supplying a washing agent along with cleansing liquid comprising an aspirator nozzle through which cleansing liquid flows to the machine, said aspirator nozzle having an aspirator opening past which cleansing liquid flows for producing a suction, a liquid washing agent container, an aspirator tube which connects the container to said opening and through which liquid washing agent may be drawn up, valve means for controlling the suction of said aspirator, and means actuated by said timer for operating said valve means.

4. In a clothes washing machine of the type having a timer for controlling automatically washing operations including the supplying of cleansing liquid to the machine, means for supplying a washing agent along with cleansing liquid comprising an aspirator nozzle through which cleansing liquid flows to the machine, said aspirator nozzle having an aspirator opening past which cleansing liquid flows, a liquid washing agent container, an aspirator tube which connects the container to said opening, movable means connected with said aspirator for rendering effective and ineffective flow of cleansing liquid past said aspirator opening to produce suction for the feeding of washing agent from said container, and means controlled by said timer for operating said movable means.

5. In a clothes washing machine of the type having a timer for controlling automatically washing operations including the supplying of cleansing liquid to the machine, means for supplying a washing agent along with cleansing liquid comprising an aspirator nozzle through which cleansing liquid flows to produce a suction, a washing agent container, an aspirator suction tube which connects the container to said opening, said tube being provided with an air bleed opening, a valve controlling said air bleed opening, and means controlled by said timer for operating said valve.

6. In a clothes washing machine of the type having a timer for controlling automatically washing operations including the supplying of cleansing liquid to the machine, means for supplying a washing agent along with

cleansing liquid comprising an aspirator nozzle through which cleansing liquid flows to the machine, said aspirator nozzle having an aspirator opening past which cleansing liquid flows to produce a suction, a washing agent container, an aspirator suction tube which connects the container to said opening, a movable member which stands in the path of flow of cleansing liquid past said aspirator opening for effecting flow of cleansing liquid over said opening to produce suction or away from it to eliminate the suction, and means controlled by said timer for operating said movable member.

7. In a clothes washing machine, an aspirator comprising a nozzle through which cleansing liquid is supplied to the machine, said nozzle having an aspirator opening past which the cleansing liquid flows, a container for a 15 washing agent, an aspirator suction tube which connects said container to said aspirator opening, and movable means for rendering flow of cleansing liquid through said tube selectively effective and ineffective for producing suction to draw washing agent through said aspirator pipe.

8. In a clothes washing machine, an aspirator comprising a nozzle through which cleansing liquid is supplied to the machine, said nozzle having an aspirator opening past which the cleansing liquid flows, a container for a washing agent, an aspirator suction tube which connects said container to said aspirator opening, movable means for rendering effective and ineffective flow of cleansing liquid through said tube to effect the pumping of washing agent through said aspirator pipe, and a projecting lip on the up stream side of said aspirator opening which 20 points angularly down stream for deflecting liquid flow past the opening.

9. In a clothes washing machine, an aspirator comprising a nozzle extending in a generally horizontal direction through which cleansing liquid is supplied to the 35 machine, said nozzle having an aspirator opening in a top portion thereof past which the cleansing liquid flows, a container for a washing agent, an aspirator suction tube

which connects said container to said aspirator opening, said aspirator tube having an air bleed opening, a valve controlling said opening, and movable means for operating said valve.

10. In a clothes washing machine, an aspirator comprising a nozzle through which cleansing liquid is supplied to the machine, said nozzle having an aspirator opening past which the cleansing liquid flows, a container for a washing agent, an aspirator suction tube which connects said container to said aspirator opening, a deflector movable into and out of the path of flow of cleansing liquid past said aspirator opening for rendering ineffective and effective suction of washing agent through said tube, and means for moving said deflector.

11. In a clothes washing machine of the type having a timer for controlling automatically washing operations including the supplying of cleansing liquid to the machine, means for supplying a washing agent along with cleansing liquid comprising an aspirator nozzle through which cleansing liquid flows to the machine, said aspirator nozzle having an aspirator opening past which cleansing liquid flows to produce a suction, a washing agent container, an aspirator suction tube which connects the container to said opening, movable means connected with 20 said aspirator for rendering effective and ineffective flow of cleansing liquid past said aspirator opening to effect the suction of washing agent from said container, a bimetal strip connected to said movable means for moving it, an electric heater for said bimetal strip, and a heater circuit for said heater which is controlled by said timer.
